(No Model.)

A. GAY.

PUNCHING MACHINE.

No. 369,597.

Patented Sept. 6, 1887.

UNITED STATES PATENT OFFICE.

ALEXANDER GAY, OF PROVIDENCE, RHODE ISLAND.

PUNCHING-MACHINE.

SPECIFICATION forming part of Letters Patent No. 369,597, dated September 6, 1867.

Application filed April 22, 1887. Serial No. 235,804. (No model.)

To all whom it may concern:

Be it known that I, ALEXANDER GAY, a citizen of the United States, residing at Providence, in the County of Providence and State 5 of Rhode Island, have invented a new and useful Improvement in Combination Punching, Cutting, and Pressing Machines, of which the following is a specification.

My invention relates to a combination 10 punching, cutting, and pressing machine adapted especially for the use of wheelwrights and blacksmiths; and it consists in a certain novel construction and arrangement of parts for service, fully set forth hereinafter, and specifically pointed out in the claims.

In the drawings hereto annexed, Figure 1 is a perspective view thereof. Fig. 2 is a central longitudinal section of same. Fig. 3 is a top plan view. Figs. 4 and 5 are detail sections.

Referring by letter to the drawings, A designates the frame or bed of the machine, having the vertical sides B B', the side B being provided near the rear end with a bearing, b, and 25 side B' with a slot or opening, b', and C is an integral plate on the outer side of the side B', having a bearing, c, therein, similar to and aligned with the bearing b, C' being a removable portion of the said plate C, the purpose 30 of which will be hereinafter described.

D is a plate secured in the front end of the frame between the sides B B', having a round opening, d, therein, and G is an eccentric power-shaft, journaled in the aligned bearings b c in the rear end of the frame, having the outer end squared and provided with a power lever or handle, H. It will be seen that 35 by means of the removable plate C' the said eccentric-shaft may be taken out of its bearings.

I is the punch-bar, sliding at the front end in the guide-opening d, and having the bifurcated rear end in which is pivoted the front end of the connecting-rod or link K, which is 45 journaled at the rear end on the eccentric shaft G.

k k are small studs on opposite sides of the said bifurcated rear end of the punch-bar, formed by the extremities of the pivot-pin k², 50 adapted to slide in guide-grooves k' k' in the inside of the sides B B'.

It will be readily seen that as the handle or lever H is oscillated the punch-bar will be reciprocated forward and backward, and will approach and recede from the block or standard L, which is provided with an opening, l, 55 therein, directly in the path of the said end of the punch-bar, and M M M are ears or flanges on the side of the said block toward the punch-bar, provided with set-screws m, adapted to 60 impinge against the sides of the die-block N when placed between the said ears and hold the same in place.

A recess or opening, O, is made in the front end of the punch-bar to receive punches, cutters, or pressing-dies and be secured therein by the set-screw o.

The bed of the machine is extended out a short distance beyond the said block or support for the dies, as seen at P, and the braces 70 P' are secured in position to brace the said block, thus forming the receptacle to catch and retain the blanks, &c., cut out by the operation of the machine.

The operation of the machine will be readily 75 understood from the foregoing description, and it will be seen that the punch-bar is adapted to have punches, cutters, and pressing-dies readily secured therein, according as one or the other is needed or desired; also, 80 the block is adapted to have the dies changed and rigidly secured in place by very simple means.

The power exerted by the punch-bar through the agency of the long lever-arm and the eccentric-shaft is very great, and as the means employed are simple, and consequently inexpensive, the implement is especially adapted for the use of carriage builders and blacksmiths.

It may, if desired, be disposed in a vertical 90 position by fastening the same to a post or other vertical support.

Having now described my invention, I claim—

1. In a punching-machine, the combination 95 of the frame A, provided with the sides B B', having the guide-grooves k' therein, the plate D at the front end of the frame, having the guide-opening d therein, eccentric power-shaft 100 G, journaled in bearings in the sides of the frame, the punch-bar I, guided at the front

end in the opening *d*, the studs *k* on the sides thereof, to operate in the grooves *k'*, and the link *K*, to connect the eccentric-shaft to the punch-bar, substantially as specified.

5 2. The combination, in a punching-machine, with the frame *A*, eccentric power-shaft *G*, journaled therein, the lever *H*, and the link *K*, of the punch-bar *I*, adapted to be reciprocated horizontally by the oscillation of the 10 said lever, having a recess, *O*, in the free end adapted to receive any desired punch, cutter, or pressing-die, and the set-screw *o*, to bear at the inner end on the said cutter, punch, or pressing-die to hold the same in place, substantially as specified.

15 3. In a punching-machine, the combination, with the frame *A*, the eccentric-shaft *G*, jour-

naled therein, punch-bar *I*, operated thereby, and the connecting-link *K* between the said shaft and the punch-bar, of the block or standard *L*, having the opening *l* therein, opposite the end of the punch-bar, ears *M M M* on the said block, and set-screws *m* in the ears *M*, adapted to be screwed inwardly to engage the die, which is placed between the said ears, and hold the same in position, substantially as specified. 20 25

In testimony that I claim the foregoing as my own I have hereto affixed my signature in presence of two witnesses.

ALEXANDER GAY.

Witnesses:

THOMAS R. ROWE,
WILLIAM A. PHILLIPS.
